BULKHEAD FOR CARS.

1,075,961.

Specification of Letters Patent.

Patented Oct. 14, 1913.

Application filed March 18, 1913. Serial No. 755,164.

To all whom it may concern:

Be it known that we, GEORGE C. BOLLER and STYLES K. CLEMENT, citizens of the United States, residing at Loomis, in the 5 county of Placer and State of California, have invented new and useful Improvements in Bulkheads for Cars, of which the following is a specification.

This invention relates to a bulkhead or 10 partition for cars.

It is the object of this invention to provide a bulkhead or partition for refrigerator cars and the like, by means of which boxes, crates, and similar articles, may be 15 securely held in the car against displacement, and to provide a bulkhead which may be moved to different points in the car and clamped securely against boxes or crates.

A further object is to provide a bulkhead 20 having vertical slats hinged at a convenient point between their ends, to permit of the lower portion of the bulkhead being swung in relation to the upper portion thereof, and to so mount the slats that they may be 25 adjusted horizontally in relation to each other to position them out of alinement with the vertical air spaces between the boxes or crates in the car.

Another object is to provide means for 30 suspending the bulkhead, which is adapted to permit of the bulkhead being moved backward and forward lengthwise of the car, and to provide a simple and efficient means for locking the upper and lower sections of the bulkhead to the sides of the car, to lock the bulkhead against movement, and by means of which the bulkhead may be 35 drawn tight against a stack of boxes, crates, or other articles.

40 A further object is to provide a bulkhead of the above character which is simple in construction, strong and durable.

The invention primarily resides in forming the bulkhead of horizontally disposed 45 spaced parallel beams and a series of vertical slats adjustably mounted on the beams and hinged intermediate their ends to form the bulkhead with a lower portion hinged in relation to an upper portion, and means 50 for connecting the ends of the bulkhead to the sides of the car and for supporting the bulkhead on movable carriages.

The invention consists of the parts and 55 the construction and combination of parts as hereinafter more fully described and

claimed, having reference to the accompanying drawings, in which—

Figure 1 is a cross section of a car, showing the bulkhead in front elevation as applied. Fig. 2 is an enlarged detail vertical 60 section on the line X—X, Fig. 1, partly in elevation. Fig. 3 is a vertical section on the line Y—Y of Fig. 1. Fig. 4 is a horizontal section on the line Z—Z of Fig. 2, partly in elevation.

In the drawings 2 indicates horizontally extending members or beams, which are adapted to extend transversely of a car 3. The beams 2 are here shown as formed of angle-irons and as arranged in pairs spaced a 70 short distance apart. Rigidly mounted on the beams 2, adjacent their outer ends, are vertically disposed slats 4, and slidably mounted on the beams 2, between the end slats 4, is a series of slats 5. The slats 4 and 5 75 are preferably formed of sheet metal channel-shaped in cross section, as shown in Fig. 4. The slideable connections between the vertical slats 5 and the horizontal beams 2 consist of tangs 6, which are struck from 80 the slats 5 and extend over the vertical portion of the angle-iron beams 2, as particularly shown in Fig. 3; this construction admitting of the slats 5 being moved freely 85 to dispose them at various distances apart on the beams 2. The slats 4 and 5, are divided at a suitable point between the upper and lower pair of beams 2, the upper and lower portions of the slats 4 and 5 being hingedly connected together by means of a pivot rod 90 7, which extends through interlocking lugs on the adjacent ends of the upper and lower portions of the slats 4 and 5 in such manner as to form a hinged connection which will permit of the lower portion of the bulkhead 95 being swung vertically in relation to the upper portion, as indicated in dotted lines in Fig. 2. The beams 2 are strengthened or reinforced by means of tension rods 8, secured at their ends to lugs 9, carried by 100 the beams 2, adjacent the end slats 4; the tension rods 8 passing over king-posts 10, mounted on the beams 2, as shown in Fig. 3.

Mounted on the outer ends of the upper and lower beams 2, between the pair of angle-irons of which the beams are formed, are rocker frames 11, which are pivotally mounted on pivot pins 12, carried by the beams 2; the rocker frame 11 constituting a lever, which is rocked as will be later described, and to 110

the outer end of which is connected a flexible member here shown as consisting of a chain 13, to the outer end of which a hook 14 is attached. The hook 14 is adapted to engage the walls of perforations 15 formed in plates 16, mounted on the sides of the car 3. Formed in the rocker frames 11 are slots 17, through which threaded stems 18 pivotally mounted at 19 on the beams 2 extend; a nut 20 being screwed on the outer end of each of the stems 18 in such manner as to bear against the outer face of the rocker frame 11 on the opposite side of the pivot pin 12 to that on which the chain 13 and hook 14 are mounted. Connected to the outer ends of the upper beam 2 are clevises 21, to which chains 22 or other flexible members are attached; the chains 22 being connected at their upper ends to carriages 23, mounted to travel horizontally on rails 24, mounted on the sides of the car 3 adjacent its roof or ceiling. The chains 22 are provided as a means for suspending the bulkhead from the carriages 23, it being manifest that any other means for suspending the bulkhead from the carriages 23 may be provided if desired.

In the operation of the invention a series of tiers or stacks of fruit, boxes, crates, and the like, are loaded in the car 3 and are arranged therein in rows, extending laterally across the car and longitudinally thereof, in the usual manner. When the desired number of stacks have been placed in one end of the car, the bulkhead is disposed in a vertical position against the face of the outermost tier; the bulkhead being moved to the desired position by means of the carriages 23 on the rails 24, which extend lengthwise of the car. The slats 5 are then adjusted on the horizontal beams 2 to position them out of alignment with the vertical air spaces between the rows of stacked boxes; the slats 5 being readily moved from side to side on the beams 2 and the pivot rod 7. The hooks 14 are then inserted in the slots 15 on the plates 16; the nut 20 on the threaded stem 18 being screwed outwardly on the latter to permit of the rocking frame 11 being moved inwardly at its outer end, and allow the hook 14 being engaged with the walls of the perforations 15. When all the hooks 14 on the ends of the upper and lower beams 2 are thus engaged with the plates 16, the nuts 20 are screwed on the threaded stems 18 to rock the rocker frames 11 on their pivot pins 12 in such manner as to take up the slack in the chains 13, and when the chains 13 are taut, pull the bulkhead tightly against the rows of stacks or boxes therebehind, thus securely clamping the boxes against movement.

When it is desired to remove the bulkhead from the front of the stack of boxes, the nuts 20 are unscrewed to admit of the hooks 14

being disengaged from the perforations 15 in the plates 16. The bulkhead may then be swung upward on its flexible connection with the carriages 23; the carriages 23 being moved backward on the tracks 24 to permit of the upper portion of the bulkhead being swung rearward over the top of the stack of boxes. The lower portion of the bulkhead being hinged in relation to the upper portion thereof permits of the bulkhead being thus withdrawn from a narrow space; the lower portion of the bulkhead retaining its vertical position as the upper portion is inclined and moved rearwardly.

When the bulkhead has been disposed horizontally in its uppermost position, the hooks 14 on the chains 13 are engaged with the rails 24 to suspend the bulkhead in a horizontal position from the rails 24. The hinged connection between the upper and lower portions of the slats 4 and 5 is such that the slats can swing in a vertical position in one direction; shoulders 25 being formed adjacent the pivot rod 7 to limit the pivotal movement of one portion of the slats 4 and 5 in relation to the other, so that the slats 4 and 5 may be disposed in a vertical position, as shown in Figs. 2 and 3.

By the use of this invention, a car 3 may be loaded with boxes, crates, and the like, for any desired portion of its length, and the boxes held securely against movement by clamping the bulkhead thereagainst, as described. This enables the shipper to load a fraction of a carload, and admits of a portion of the shipment being delivered at various points; the bulkhead being swung against the ceiling of the car when it is desired to remove part of the shipment, and then restored to its clamping position against the outermost tiers of the remainder of the load.

If there is sufficient clear space in front of the stacked boxes, the bulkhead may be swung forwardly on its suspending connections instead of being moved rearwardly, as previously described.

As a means for preventing the bulkhead from rising when clamped against a tier of boxes, the lower ends of the slats 4 and 5 are bent inwardly to form projections 4' which are adapted to catch under the stack of boxes piled next to the bulkhead; the weight of the boxes thus resisting any tendency of the bulkhead to move in an upward direction.

Having thus described our invention, what we claim and desire to secure by Letters Patent is:

1. An adjustable bulkhead for cars comprising parallel beams, end slats to which the beams are rigidly attached, a series of slats carried by the beams between the end slats, and tangs on the slats engaging the beams to form a slidable connection therewith.

2. A bulkhead for cars comprising spaced parallel horizontally disposed angle-iron beams, end slats connecting the beams adjacent their ends, a series of intermediate slats, tangs on said slats slidably engaging the vertical leaf of the angle iron beams, and hinged joints formed in the slats to allow the lower portion of the slats to be swung in relation to their upper portion. 55
- 10 3. A bulkhead for cars comprising spaced parallel horizontally disposed angle iron beams, tension rods secured at their ends to the beams, king-posts on the beams intermediate their ends over which the tension rods 60 pass, end slats connecting the beams adjacent their ends, a series of intermediate slats, tangs on said slats slidably engaging the vertical leaf of the angle iron beams, and hinged joints formed in the slats to allow the lower portion of the slats to be swung in relation to their upper portion. 65
- 15 4. An adjustable bulkhead for cars comprising parallel beams, end slats connecting the beams, intermediate slats slidably attached to the beams, means for suspending the beams, rocking frames on the ends of the beams, hooks carried by said rocking members, stationary plates formed with perforations engageable by said hooks, and means 70 for rocking and locking said frames to exert a pull on the hooks and plates acting to move the bulkhead rearwardly. 75
- 20 5. An adjustable bulkhead for cars comprising parallel beams, end slats connecting the beams, intermediate slats slidably attached to the beams, means for suspending the beams, rocking frames on the ends of the beams, hooks carried by said rocking members, stationary plates formed with perforations engageable by said hooks, a threaded stem on the beams, and a nut on said stem 80 engageable with the rocking frame and adapted to rock the latter to exert a pull on the hooks and plates when screwed on the threaded stem and cause the bulkhead to move rearwardly. 85
- 25 6. An adjustable bulkhead for cars comprising parallel beams, end slats connecting the beams, intermediate slats slidably attached to the beams, means for suspending the beams, rocking frames on the ends of the beams, hooks carried by said rocking members, stationary plates formed with perforations engageable by said hooks, a threaded stem on the beams, a nut on said stem 90 engageable with the rocking frame and adapted to rock the latter to exert a pull on the hooks and plates when screwed on the threaded stem and cause the bulkhead to move rearwardly. 95
- 30 7. In an adjustable bulkhead for cars, the combination of a pair of carriages mounted to travel lengthwise of a car, a horizontal beam pivotally suspended from said carriages extending transverse of the car, end slats rigidly secured to said beam, a second beam carried by said slats, a series of intermediate slats slidably mounted on said beams for lateral adjustment, aligned pivot joints formed in the intermediate and end slats between the beams, hooks on the ends of the beams, means on the car engageable by the hooks to hold the bulkhead formed by the slats and beams in a vertical position, and screw elements coöperating with the hooks and beams by which the bulkhead may be pulled rearwardly. 100
- 35 8. An adjustable bulkhead for cars comprising parallel beams, end slats to which the beams are rigidly attached, a series of slats slidably mounted on the beams between the end slats, and projections on said slats engageable with a stack of crates adjacent the bulkhead. 105
- 40 9. An adjustable bulkhead for cars comprising parallel beams, end slats connecting the beams, adjustable means for connecting the beams, adjustable means for suspending the ends of the beams to clamp the bulkhead against a stack of crates under pressure, and means engageable with the stack of crates to prevent vertical movement of the bulkhead. 110

In testimony whereof we have hereunto set our hands in the presence of two subscribing witnesses.
